UNITED STATES PATENT OFFICE

WILLIAM SCOTT SILVER, OF HAVRE DE GRACE, MARYLAND

SEALING MACHINE

Application filed February 3, 1928. Serial No. 251,643.

This invention relates to certain new and useful improvements in sealing machines and has for its particular object the provision of a sealing machine for corrugated paper or fiber boxes.

The principal object of the invention is the provision of a machine having a rotatable table carrying box holding supports, on which the flexible containers, such as boxes or the like, are placed so that one of their ends may be securely sealed with suitable adhesive or sealing tape.

A further object of the invention is the provision of a machine having a rotatable table carrying boxes on supporting members, so that when the containers are placed thereon they may be positioned accurately under the sealing plate so that the given ends of the boxes or containers may be securely sealed.

A still further object of the invention is the provision of a sealing machine equipped with hinged arms carrying sealing plates and a pressure means whereby said plates may be locked into active container engaging position so that a given end of the container may be securely and permanently sealed.

A still further object of the invention is the provision of a sealing machine equipped with means whereby the pressure on the end of the container being sealed may be regulated in accordance with the required amount of pressure needed.

A still further object of the invention is the provision of a sealing machine equipped with a rotatable table carrying container supports, a plurality of laterally projecting hinged arms carrying sealing plates, and an adjustable pressure locking means whereby said sealing plates may be locked in active engagement with the end of the container to be sealed, so as to assure of a positive sealing action.

With these and other objects in view, the invention consists in certain novel features. combination and arrangement of parts as will be hereinafter more fully described, illustrated in the accompanying drawings, and claimed.

In the drawings,
50 Figure 1 is a side elevational view of my

improved sealing machine, as made in accordance with this invention;

Figure 2 is a transverse sectional view taken on the line 2—2 of Figure 1;

Figure 3 is a longitudinal sectional view 55 taken on the line 3—3 of Figure 1;

Figure 4 is a fragmentary detailed perspective view, illustrating the machine in inactive position; and,

Figure 5 is a fragmentary enlarged detailed perspective view, illustrating the initial sealing movement of my improved machine.

Referring to the drawings, the numeral 5 indicates a base preferably of circular formation, and extending upwardly from the center of said base is a bearing 6, in which is rotatably mounted a vertical standard 7, and secured to the standard 7 intermediate its ends, is an annular table 8 provided on its underside 70 with relatively spaced depending legs 9, having mounted in their lower terminals, rollers 10, which have contact with the upper surface of the base 5.

The table 8 is rigidly supported to the 75 standard 7 by suitable brace rods 11, and it can be readily understood that the even travel of the table is accomplished by virtue of the rollers 10 and their association with the table 8.

Mounted on the upper side of the table 8 is a plurality of relatively spaced box supports 12, on which is adapted to be removably placed, a container or box 13, so as to permit its end 14 to be closed and sealed, as will be 85 hereinafter more fully described.

Secured to the standard 7 above the table 8, is a plurality of relatively spaced laterally or radially extending arms 15, which are rigidly connected together by suitable brace rods 16, 90 and to the outer ends of these arms 15 are hinged, as at 17, pressure arms 18, and to the underside of these arms 18 are pivotally secured, as at 19, pressure plates 20. The pressure plates 20, which are pivotally secured, as at 19, to the arms 18, are so pivoted as to permit them to have contact with the entire area of the end 14 of the container 13, so that when pressure is applied to said plates through the medium of the arms 18, the entire 100

end 14 will be permanently and securely sealed.

To provide means whereby said pressure arms 18 may be held in pressure contact with the container 13, I pivotally secure, as at 21, to the upper end of the standard 7, a plurality of barrels 22, in which is adjustably secured one end of the pressure locking lever 23, which has its inner end surrounded by a coil spring 24, so that the tension on said pressure lever may be regulated. Pivoted as at 25, to the pressure lever 23, is a link structure 26, the free ends of said link structure being pivoted, as at 27, to the pressure arms 18.

15 The free end of the pressure lever 23 has an angular extension 28, constituting a handle, whereby said lever may be manipulated to either raise the pressure arms 18, as illustrated in Figure 4, or hold same in 20 positive contact with the box supports 12, as illustrated in Figure 1.

When the pressure lever 23 is closed in the position illustrated in Figure 1, the majority of said lever is forced beyond the center of the 25 pivot 25, so as to set up a locking action to retain the pressure arm and its plate in positive sealing contact with the end of the container being sealed.

It can be readily understood that when the 30 device is in operation the operator places the containers on the supports 12, folds the ends inwardly after first applying a suitable adhesive thereto, brings the arm 18 carrying the plate 20 into contact with said ends of the 35 containers, pressing the lever 23 into locked position, which automatically exerts pressure through the link structure 26 to the arm 18 through the plate 20 to the container end, so as to permanently seal the latter in closed position.

40 Having thus described my invention, what I claim as new is:

A box sealing machine comprising a stationary base, a standard rotatably mounted 45 at the central axis of said base, a table secured to said standard and equipped with rollers and having contact with said base whereby even travel of the standard and table may be had relative to the base, container supporting members secured to said 50 table, stationary radially extending arms secured to the standard above said container supports, pressure arms hingeably secured to the outer terminals of said first named arms 55 and overlying said container supports, pressure plates carried by said pressure arms, and an adjustable locking means associated with said standard and comprising pivoted links 60 whereby said pressure plates and arms may be held in firm contact with said container supports.

In testimony whereof he hereunto affixes his signature.

WILLIAM SCOTT SILVER.
